UNITED STATES PATENT OFFICE.

ARTHUR G. SLOCUM, OF ENSIGN, KANSAS.

CUT-OFF FOR OIL BURNERS.

Application filed March 23, 1923. Serial No. 627,141.

To all whom it may concern:

Be it known that I, ARTHUR G. SLOCUM, a citizen of the United States, residing at Ensign, in the county of Gray and State of Kansas, have invented certain new and useful Improvements in Cut-Offs for Oil Burners, of which the following is a specification.

This invention relates to a cut-off for oil burners and particularly to a construction adapted to be automatically operated by the overflow from a burner pan.

In prior constructions of cut-off devices of this character difficulty has been experienced in securing a positive operation of the cut-off valve and an accurate and prompt release of the closing means for this valve as the overflowing liquid collects in the receptacle for operating a trip mechanism.

This invention therefore seeks to secure a simple and efficient construction by which the cut-off valve is positively operated by a tension means and is normally sustained in inoperative position by a trip lever having an arm carrying a receptacle to actuate the lever by the collected liquid therein.

A further object of the invention is to provide a construction embodying two active parts and adapted to be conveniently mounted upon the feed connection for an oil burner and not requiring skilled labor for that purpose.

Other and further objects and advantages of the invention will be hereinafter set forth and the novel features thereof defined by the appended claims.

In the drawing:

Figure 1 is a perspective showing the invention applied.

Figure 2 is an enlarged top plan of the cut-off and trip lever on the line 2-2 of Figure 1.

Figure 3 is a detail perspective of the supporting plug for the trip lever; and

Figure 4 is a detail elevation of the free end of the valve lever and cooperating trip lever.

Like numerals refer to like parts on the several figures of the drawings.

The numeral 10 designates an oil burner which may be of any desired construction or configuration, for instance of the type shown in my co-pending application filed February 9th, 1923, Serial Number 618,001, which involves a retort 11 disposed above the burner and a connecting support 12 communicating therewith. Surrounding

the burner is the usual drip or overflow pan 13 adapted to retain sufficient oil to be used for priming or starting purposes. Extending through the bottom of this pan is an overflow pipe 14 the upper end of which is of sufficient height above the bottom of the pan to always retain therein a body of oil for starting purposes.

As showing an efficient and simple method of supporting this invention I have connected a T-coupling 15 with the pipe section 16 leading to the burner and laterally from this coupling the feed pipe 17 is extended and provided with a cut-off cock or valve 18. For the purpose of actuating this valve a lever 19 is connected to the stem thereof and extends substantially parallel with the feed pipe toward the coupling 15. This lever is maintained under tension in any desired manner, for instance by means of an adjustable weight 20 slidingly mounted thereon. By changing the position of this weight relative to the free end of the lever the tension necessary to positively actuate the valve may be definitely determined.

For the purpose of sustaining the lever 19 in its raised or inoperative position so that a continued feed of fuel to the burner is maintained, I have provided a trip lever 21 which is formed with an angular or lateral arm 22 and pivotally mounted at 23 upon a support 24 carried by the T-coupling 15. This support may constitute a plug member, as indicated in Figure 3, having a threaded portion 25 at its upper end to enter the coupling and provided with the pivoting lug 26 at its lower portion. Above the lug 26 a stop member 27 is provided and disposed in the path of travel of the trip lever 21 so as to limit the movement of this lever away from the end of the valve lever 19. The angular arm 22 of the trip lever carries a supporting frame 28 for a receptacle 29 which is disposed beneath the outlet from the overflow 14. This receptacle may be adjustably mounted upon the arm by means of a clamping screw 30, as shown in Figure 1, and such adjustment determines the amount of liquid necessary in the receptacle 29 to withdraw the trip lever from engagement with the valve lever.

For the purpose of facilitating the movement of these levers upon each other the valve lever is preferably formed at its outer end with a curved seat 31, the inner portion of which terminates in a stop 32 while the

free end 33 of the trip lever is curved to correspond with said seat. In setting the parts, the trip lever may therefore be pressed into contact with the stop 32 and when said lever is actuated it travels upon the curved face of the seat which offers the minimum of resistance and renders the device sensitive in its action.

In the operation of the invention the feed 10 of oil to the burner is maintained and may be normally regulated in any desired manner. If there is an over or excess feed of oil to the burner it will collect in the pan and the overflow therefore passes to the receptacle carried by the actuating arm of the trip lever, which swings said lever from beneath the tensioned valve lever and the latter is closed by tension or gravity so as to completely cut off the flow of oil until 20 the parts are again restored. In this construction the receptacle may be readily removed from the trip lever and emptied when it is desired to reset this lever beneath the valve lever and the support for the receptacle by its adjustment will determine the body of liquid therein necessary to swing the trip lever in its releasing action, and the degree of this movement is limited by the stop member so as to prevent a discharge 30 or displacement of the liquid in the receptacle. The invention presents a very simple and efficient construction and arrangement of the several parts adapted to be readily applied to a burner by a single coupling member and secures a positive and definite operation of the valve and trip lever under all conditions of use.

What I claim is:

1. An oil burner provided with an over-

flow pan, a feed pipe to said burner, a rotary 40 controlling valve in said pipe, a tensioned lever carried by the stem of said valve and projected beneath said pan, a support dependent from said burner, an angular trip lever pivoted upon said support and having 45 an arm beneath the free end of said valve lever, a horizontal arm extended beneath the overflow pan, and a receptacle supported upon said horizontal arm to receive the overflow and thereby actuate said lever to release 50 the feed valve for closing movement.

2. An oil burner provided with an overflow pan, a coupling secured centrally to said burner, a valved feed pipe at one side of said coupling, a supporting plug mounted in 55 said coupling and provided with a pivot, an angular trip lever disposed upon said pivot and having a vertical arm, a lever from the feed pipe valve for automatically closing the same and normally supported at its free end 60 by said arm, and a receptacle carried by the opposite angular arm of the trip beneath said pan and adapted to receive liquid therefrom to actuate the trip lever and release 65 the valve lever for closing the valve.

3. An oil burner provided with an overflow pan, a T-coupling secured to said burner, a valved feed pipe at one side of said coupling, a supporting plug mounted in said coupling and provided with a pivot, an 70 angular trip lever disposed upon said pivot, a lever from the valve in said feed pipe supported by said trip lever, and a stop provided upon said plug to limit the movement of the trip lever away from the valve lever. 75

In testimony whereof I affix my signature.

ARTHUR G. SLOCUM.
